ABSTRACT: A container for beverage cans and the like. The container has a hollow circumferentially continuous sidewall means which from top to bottom has a dimension sufficiently great to accommodate a plurality of cans stacked one upon the other. A bottom wall extends across and is connected with the sidewall means to support the cans surrounded by the latter, and a cover is releasably carried by the sidewall means at its top end for releasably covering the interior space where the cans are accommodated. The sidewall means includes inner and outer walls defining between themselves and a hollow chamber for accommodating a medium which may be used for chilling cans within the container, and the space between the inner and outer walls is closed at the bottom by the bottom wall while at the top an endless strip extends along and is fixed with the top edges of the inner and outer wall to close the interior space therebetween.

CONTAINER FOR BEVERAGE CANS

BACKGROUND OF THE INVENTION

The present invention relates to containers.

In particular, the present invention relates to containers for articles such as beverage cans. Thus, the present invention relates in particular to that type of container which is adapted either to maintain chilled beverage cans in a chilled condition or to chill the cans to a temperature lower than room temperature and then to maintain the cans in a chilled condition for a substantial period of time.

Although containers of this general type are indeed well-known in a wide variety of forms, all the known constructions leave much to be desired. For example, with all the known constructions, any container which can accommodate a plurality of cans is undesirably bulky, providing considerable inconvenience in transporting such a container. For example, it is common to support the beverage cans in a single layer where the beverage cans stand in side-by-side relation, in a manner similar to their arrangement in the so-called six-pack assemblies. As a result of this bulky arrangement it does not become possible to accommodate the cans in an article such as an attache case, a golf bag, or the like.

Furthermore, the known constructions of this general type are relatively complex and undesirably expensive. Thus, there are some known containers of this type where hollow walls are individually swingable with the respect to each other to define the container, these hollow walls being individually filled with a suitable medium for refrigerating purposes.

A further disadvantage of the known constructions resides in the fact that the refrigerating medium is permanently contained within a hollow chamber, which necessitates an undesirable permanent increase in the weight of the entire assembly even when it is not used for chilling beverage cans or the like.

Furthermore, conventional containers are not capable of being adapted to the requirements of different individuals so as to be carried about in the most convenient manner.

SUMMARY OF THE INVENTION

It is accordingly a primary object of the present invention to provide a container of the above general type which will avoid all the above drawbacks.

In particular, it is the object of the invention to provide a container which is capable of accommodating a plurality of articles such as beverage cans in such a way that the container with the cans therein can easily be accommodated in an attache case, a golf club bag, or the like. Furthermore, it is the object of the present invention to provide a construction of this type which is far simpler and less expensive than previously known structures.

In addition, it is the object of the invention to provide a structure of this type which while being simple and inexpensive is also exceedingly strong so that a long life of the structure of the invention is assured, even under conditions of relatively rough use.

Furthermore, it is the object of the invention to provide a container of the above general type which easily can be adapted to the requirements of any individual for the purpose of achieving the most convenient manner of carrying the container about.

Also, it is the object of the invention to provide a construction of this type which, when it is not in use, will be of extremely light weight.

The container of the invention has a hollow circumferentially continuous sidewall means the dimension of which from top to bottom is sufficiently great to accommodate a stack of beverage cans or the like situated one upon the other. A bottom wall extends across and is connected to the sidewall means to form a closure for the bottom of the container and to support the cans therein. A cover is releasably carried by the sidewall means at its top end for releasably closing the interior

of the container. The sidewall means has an inner wall and an outer wall spaced from the inner wall and defining therewith the hollow interior of the sidewall means which is adapted to accommodate a medium for chilling the cans within the container. The bottom wall extends across this space between and is connected to the bottom edges of the inner and outer walls so as to close the hollow interior defined between the inner and outer walls. A continuous strip extends along and is fixed to the top edges of the inner and outer walls so as to close the hollow space between these walls at the top end of the sidewall means, and the cover rests on this strip when it closed the container means. Thus, a suitable refrigerating medium may be accommodated between the inner and outer walls of the sidewall means.

Other objects and advantages of the invention will in part be obvious and will in part be apparent from the specifications.

The invention accordingly comprises the features of construction, combinations of elements, and arrangement of parts which will be exemplified in the constructions hereinafter set forth, and the scope of the invention will be indicated in the claims.

BRIEF DESCRIPTION OF THE DRAWINGS

25 For a fuller understanding of the invention, reference is had to the following description taken in connection with the accompanying drawings, in which:

FIG. 1 is a perspective elevation of a container of the invention;

30 FIG. 2 is a transverse sectional elevation taken along line 2-2 of FIG. 1 in the direction of the arrows and showing the structure in greater detail and at a scale which is enlarged as compared to FIG. 1; and

35 FIG. 3 is a sectional plan view taken along the line 3-3 of FIG. 2 in the direction of the arrows.

DESCRIPTION OF A PREFERRED EMBODIMENT

Referring now to the drawings, the container 10 of the 40 present invention which is illustrated in FIG. 1 includes a circumferentially continuous sidewall means 12. This sidewall means 12 is made up of an inner wall 14 and an outer wall 16 which is spaced from the inner wall 14 to define therewith a hollow interior space 18, so as to form the hollow circumferentially continuous sidewall means 12. The walls 14 and 16

45 are made of a single layer of sheet material which preferably is a metal such as aluminum. As is apparent from FIG. 3, the configuration of the sidewall means 12, in cross section, is not precisely oval or elliptical, but rather is that of a pair of flat front and rear walls extending parallel to each other and joined at their ends by semicircular walls. In this way it becomes possible, by suitable dimensions of the container 10 from side-to-side to accommodate in the interior of the container a pair of stacks of cans 20 shown in side-by-side relation in FIG. 3.

50 Thus, the inner wall 14 and outer wall 16 of the sidewall means 12 are each made of a single layer of sheet material which preferably is a metal such as aluminum. The dimension of the sidewall means 12 from top to bottom is sufficiently great to accommodate a stack of cans 20. Thus, as particularly apparent from FIG. 2 each stack includes three cans 20 situated one upon the other in the illustrated example. In this way the container 10 of the invention can accommodate six cans

55 20 arranged in two stacks in side-by-side relation, and as a result the dimension of the container means 10 from front-to-rear is so small that the entire container 10 can easily be accommodated in an attache case, a golf bag, or the like.

The container 10 further includes a bottom wall 22 which 60 may be made of the same sheet metal as the walls 14 and 16 and which is also in the form of a single layer of sheet material. This wall 22, which may also be made of aluminum, if desired, extends across the bottom edges of the walls 14 and 16 and is fluidtightly fixed to these bottom edges in any suitable way, so that the bottom wall 22 serves not only to support cans 20 in

the interior of the container 10 but also to fluidtightly close the space 18 between the walls 14 and 16, at the bottom end of this space.

The sidewall means further includes an upper endless strip 24 which may also be made of a metal such as aluminum and which extends between and is fixed to the top edges of the walls 14 and 16 in a fluidtight manner, as by being welded or otherwise connected with these walls, in the manner indicated schematically in FIG. 2. Thus, the endless strip 24 which has the configuration of the horizontal cross section of the space between the walls 14 and 16, closes the space 18 at its top end.

The strip 24 is formed with at least one opening 26 having the stepped configuration illustrated at the upper left part of FIG. 2. This opening 26 is adapted to receive a plug 28 made of rubber or other suitable flexible resilient material, so that whenever desired the plug 28 can be removed. When the plug 28 is in the position shown in FIG. 2, it fluidtightly closes the opening 26 so as to maintain the interior space 18 closed off from the outer atmosphere. It will be noted that the plug 28 is substantially flush with the upper surface of the strip 24, when closing the interior space 18, so that the plug does not extend upwardly beyond the strip 24.

This interior space 18 of the sidewall means 12 is adapted to receive a medium which may simply be tap water which can be introduced through the opening 26 when the plug 28 is removed. Such a medium will extend to an elevation somewhat short of the strip 24 so as to leave an expansion space 30 within the chamber 18 at the top thereof. With such a medium within the space 18, the entire container can be placed in a freezer so that the medium will become chilled forming ice, for example. Of course, with the tap water or the like situated within the space 18, the plug 28 is replaced.

The container 10 further includes a removable cover 32 made of any suitable plastic or metal sheet material and having a depending flange 34 extending around and frictionally engaging the exterior side surface of the wall 16 at the top end of the latter, so that the cover 32 is simply frictionally retained on the container. It will be noted that when the cover 32 is in a position closing the container it simply rests upon the strip 24. Because the plug 28 does not project upwardly beyond the strip 24, the cover 32 rests directly on the strip 24 along the entire length thereof so that the single sheet which forms the cover 32 does not extend the interior space upwardly beyond the strip 24.

The container 10 of the invention is completed by a strap 36 made of any suitable plastic sheet material or the like and forming a handle or sling by which the entire container 10 can conveniently be carried about. A button 38 permanently fixes one end of the strap 36 to the sidewall 16 with this button 38 having a fluidtight connection with the wall 16. The other end of the strap 36 has a buttonhole opening or the like capable of slipped onto the head 40 of a second button 42 which is fluidtightly fixed to the wall 16 beneath the button 38. Thus, the strap 36 may assume the solid-line position indicated in FIGS. 1 and 2, enabling the strap 36 to extend around the shoulder of the individual who carries the container 10, so that in this way the container can be carried about in a very comfortable manner.

However, the wall 16 has as its front portion a second button 44 identical with the button 40 and capable of accommodating the strap 36 when it has the dot-dash line position shown at the top of FIG. 2, so that in this case the strap extends over the top of the container and can conveniently be grasped in the hand of the operator to be carried about very conveniently.

In order to use the container of the invention the operator will remove the plug 28 and locate the tap water or the like in the space 18, leaving a free space 30 as described above. Then the entire container, after the plug 28 has been replaced, is placed in a suitable freezer so that the medium in the space 18 will become suitably chilled.

Thereafter, the user of the container may place the cans 20 therein, and if these cans are initially chilled they will remain

chilled, while if they are put are put in at room temperature, the refrigerated medium in the space 18 will serve to chill the containers and maintain them chilled.

With the cover 32 placed on the container the entire container 10 may be accommodated in a golf bag, attache case, or the like, as pointed out above. However, it is also possible to use the strap 36 in either of its positions for carrying the container about.

It is to be noted that although possible for heat to flow readily through the walls 16, nevertheless it has been found from experience that the structure described above and shown in the drawing is capable of maintaining the cans 20 chilled for a length of time sufficiently great for almost all purposes.

Thus, the simple container consists only of the inner and outer walls 14 and 16 and the bottom wall 22 all of which are formed of a single layer of sheet metal, so that the cost of the container is very low while at the same time it is exceedingly rugged since the metal walls can withstand rough usage without any particular damage, and even if the outer walls 16 should become slightly dented, for example, there still will be no undesirable influence on the operation of the structure.

When the structure is not in use, the plug 28 can be removed so that the refrigerating medium can be poured out. As a result, when the structure of the invention is not used it is extremely light, as contrasted with known constructions where the refrigerating medium is permanently maintained in the walls of the structure so that even when it is not used it is quite heavy to carry about.

The strap 36 of course provides an added convenience which also is not available with known constructions.

It will thus be seen that the objects set forth above, among those made apparent from the preceding description, are efficiently attained and, since certain changes may be made in the above constructions without departing from the spirit and scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

I claim:

1. A container for beverage cans and the like, comprising an elongated hollow circumferentially continuous sidewall means having a dimension from top to bottom sufficiently great to accommodate a plurality of cans stacked one upon the other, a bottom wall fixed to and extending across the bottom of said sidewall means to a form a wall on which the stack of cans rests, and a removable cover for removably covering said sidewall means at the top thereof, said sidewall means including a single continuous, uninterrupted metal sheet having top and bottom edges and forming an inner wall, said inner wall having a pair of opposed flat parallel front and rear wall portions and a pair of opposed end wall portions of semicircular cross section, and said sidewall means including a second continuous, uninterrupted sheet of metal having top and bottom continuous, uninterrupted peripheral edges and surrounding and spaced from said inner wall to form an outer wall spaced from said inner wall and defining with the latter a chamber for receiving a medium for chilling cans surrounded by said sidewall means, said second sheet of metal also having a pair of opposed flat parallel wall portions and a pair of opposed end wall portions of semicircular cross section, and the flat and semicircular wall portions of said outer wall being in opposed substantially parallel spaced relation respectively with the flat and semicircular portions of said inner wall, said bottom wall closing the space between said inner and outer walls at the bottom ends of the latter, and said bottom wall also being formed of a single sheet of metal extending across and beyond the bottom edge of said inner wall radially outwardly to the bottom edge of said outer wall, said inner and outer

walls having equal heights so that the top edges thereof are at the same elevation, and a circumferentially continuous strip extending along said top edges of said inner and outer walls and closing the space therebetween at the top end of said space, said cover when in a closed position resting on said strip, said cover also being composed of a single sheet and said cover engaging said strip along the entire length thereof and forming with said inner wall an interior container space which does not extend above said strip, said sidewall means having a dimension between said semicircular end portions thereof sufficiently great to accommodate a plurality of stacks of cans in side-by-side relation.

2. The combination of claim 1 and wherein said strip is formed with an opening through which access may be had to the space between said inner and outer walls of said sidewall means, and a plug carried by said strip for releasably closing said opening thereof, said plug when in a closed position closing the latter opening being substantially flush with a top surface of said strip so that said plug does not extend above said strip and thus enables said cover to lie flush against said strip along the entire length thereof.

I claim:

1. A container for beverage cans and the like, comprising an elongated hollow circumferentially continuous sidewall means having a dimension from top to bottom sufficiently great to accommodate a plurality of cans stacked one upon the other, a bottom wall fixed to and extending across the bottom of said sidewall means to form a wall on which the stack of cans rests, and a removable cover for removably covering said sidewall means at the top thereof, said sidewall means including a single continuous, uninterrupted metal sheet having top and bottom edges and forming an inner wall, said inner wall having a pair of opposed flat parallel front end rear wall portions and a pair of opposed end wall portions of semicircular cross section, and said sidewall means including a second continuous, uninterrupted sheet of metal having top and bottom continuous, uninterrupted peripheral edges and surrounding and spaced from said inner wall to form an outer wall spaced from said inner wall and defining with the latter a chamber for receiving a medium for chilling cans surrounded by said sidewall means, said second sheet of metal also having a pair of opposed flat parallel wall portions and a pair of opposed end wall portions of semicircular cross section, and the flat and semicircular wall portions of said outer wall being in opposed substantially parallel spaced relation respectively with 45

the flat and semicircular portions of said inner wall, said bottom wall closing the space between said inner and outer walls at the bottom ends of the latter, and said bottom wall also being formed of a single sheet of metal extending across and beyond the bottom edge of said inner wall radially outwardly to the bottom edge of said outer wall, said inner and outer walls having equal heights so that the top edges thereof are at the same elevation, and a circumferentially continuous strip extending along said top edges of said inner and outer walls and closing the space therebetween at the top end of said space, said cover when in a closed position resting on said strip, said cover also being composed of a single sheet and said cover engaging said strip along the entire length thereof and forming with said inner wall an interior container space which does not extend above said strip, said sidewall means having a dimension between said semicircular end portions thereof sufficiently great to accommodate a plurality of stacks of cans in side-by-side relation.

2. The combination of claim 1 and wherein said strip is formed with an opening through which access may be had to the space between said inner and outer walls of said sidewall means, and a plug carried by said strip for releasably closing said opening thereof, said plug when in a closed position closing the latter opening being substantially flush with a top surface of said strip so that said plug does not extend above said strip and thus enables said cover to lie flush against said strip along the entire length thereof.

3. The combination of claim 1 and wherein a strap is carried by said sidewall means at the exterior thereof to facilitate carrying of the container, said strap having one end located at a predetermined position of the container, and a pair of fastening means carried by the container for releasably fastening the other end of the strap thereto at different locations situating the strap in one position at only one exterior side surface of said sidewall means and in another position extending over the top of said sidewall means.

4. The combination of claim 1 and wherein said sidewall means has from front-to-rear a dimension sufficiently great only to accommodate a single can in the front-to-rear direction.

5. The combination of claim 4 and wherein said dimensions of said sidewall means are sufficiently great to accommodate two stacks of cans in side-by-side relation with three cans being situated in each stack.
